UNITED STATES PATENT OFFICE.

RUFUS ANDERSON, OF PEEKSKILL, NEW YORK.

AUTOMATIC TELEGRAPH.

SPECIFICATION forming part of Letters Patent No. 296,376, dated April 8, 1884.

Application filed March 17, 1883. (No model.)

To all whom it may concern:

Be it known that I, RUFUS ANDERSON, a citizen of the United States, residing at Peekskill, in the county of Westchester and State of New York, have invented new and useful Improvements in Telegraphic Transmitting-Instruments, of which the following is a specification.

This invention relates to improvements in that class of automatic telegraphic transmitting-instruments in which the message to be transmitted is placed in insulating-ink upon the surface of a metallic drum, which is afterward rotated under a contact-roller which follows the spiral line of characters composing the message.

In this class of instruments as heretofore constructed the metallic drum is rotated at first slowly under a pen which has a rectilinear travel across the face of the drum, and is operated to deposit the insulating-ink. After the inscription of the message is completed and the ink has dried, the drum is rotated with a much more rapid motion under the contact-roller.

The objects of my improvement are, first, to simplify the devices for throwing the contact-roller into and out of contact with the drum, and to cause the lateral travel of said roller to commence and cease simultaneously with the commencement and cessation of the contact of the roller with the drum, respectively; and, second, to simplify the mechanism for changing the speed of the drum.

The invention consists in certain novel constructions and combinations of devices, which will be hereinafter fully described, and pointed out in the appended claims.

In the accompanying drawings, Figure 1 is a vertical section of a transmitting apparatus constructed according to my invention, the plane of section being indicated by the line xx , Fig. 2. Fig. 2 is a top view of the apparatus. Fig. 3 is a side view of the drum with a portion of its wall broken away to show the burner within the same. Fig. 4 is a detail cross-section illustrating the sliding carriage, its support, and the contact-roller and its operating devices. Fig. 5 is a detail top view of the parts shown in Fig. 4. Fig. 6 is a diagram illustrating the devices for giving the slow motion to the drum.

B E' is a frame, in which is supported the shaft S, upon which is mounted the drum A. Upon the shaft is a loose pulley, S', moved longitudinally thereon by means of a shifting-lever (not shown) taking into the recess s in the sleeve of the pulley. On the shaft S is fixed a clutch, e, with which the pulley may be locked, so that the shaft and drum may be rotated directly with the pulley, and at a high rate of speed. Upon upward extensions b of the sides of the frame is secured a horizontal carriage-support, H, having its edges dovetailed to receive a correspondingly-dovetailed carriage, G, which slides on said support in a direction parallel with the axis of the drum. The carriage-support H is slotted longitudinally through its center, and through the slot is arranged a screw-shaft, E, having its bearings in the end walls of the slot. To a post, d, projecting upward from the rear edge of the carriage, is pivoted an arm, D, to which is secured a stout finger-spring, k, at the outer end of which is mounted the contact-roller K, which is arranged to be brought in contact with the surface of the drum.

To one side of the arm D is secured a plate, F, projecting downward through a slot in the carriage, and having its lower edge formed as a segmental knife-edge, to engage with the screw-shaft E. From the top of the carriage rises a short standard, l, Fig. 5, directly opposite the plate F, and to this standard on the side next said plate is centrally pivoted a disk, L, having a handle, l'. From this disk an eccentric pin, l'', projects loosely through the arm D and plate F. It will now be observed that when the arm l' is swung to the right, or in the direction indicated by the arrow, the eccentric pin l'' will force downward the arm D and plate F, bringing the knife-edge of the plate into engagement with the screw E, and the roller K simultaneously into contact with the drum. If the screw-shaft E be now rotated, the carriage will be caused to travel upon its support and carry the contact-roller across the face of the drum, and if the drum be at the same time rotated upon its axis it is obvious that the roller will have a spiral line of contact with the surface of said drum.

Upon a separate carriage, G', Fig. 2, is mounted the pen P, which is constructed and operated for placing the message upon the

drum in the manner shown in the patent of William A. Leggo, No. 238,929, dated March 15, 1881. The letter *p* indicates a pivoted knife-edge, which may be used to bring the carriage into engagement with the screw-shaft when the pen is to be used; but this knife-edge is not connected with the pin.

Upon one end of the screw-shaft *E*, which projects through its bearing, is fixed a gear-wheel, *E'*, which meshes with a similar gear-wheel, *E''*, fixed upon the shaft *S*. When the pulley *S'* is clutched to the shaft and rotated by means of a belt, a rapid rotary motion will be given to the shaft, and this rapid motion will be transmitted, through the gear-wheels *E''* and *E'*, to screw-shaft *E*, and the carriage *G* will be caused to have a rapid travel on its support if the knife-edge plate *F* be brought into engagement with the screw-shaft, as hereinbefore described. This rapid motion is given to the parts when the message is being transmitted. As explained, however, in the patent of Leggo, heretofore referred to, the drum and carriage must have a much slower motion when the pen is being used, in order that the operator may have time to properly write his message, and in order to give this slower motion a separate set of devices is used for transmitting motion from the pulley *S'* to the drum and carriage. From said pulley a belt, *S³*, passes downward around a small pulley, *w*, fixed upon a transverse shaft journaled in suitable bearings below the shaft *S*, and from this small pulley *w* a belt, *S⁴*, passes upward around the belt-wheel *W'*, which is carried at one end of a short shaft, *S⁵*, mounted in a sleeve-bearing carried at one end of a lever, *N*, pivoted at the top of a standard, *N'*. At the other end of the short shaft *S⁵* is a pinion, *S⁶*, arranged to mesh with the gear-wheel *E''* upon the shaft *S*. When the outer end of the lever *N* is depressed, said pinion *S⁶* will be engaged with the gear-wheel *E''*, and the belt *S⁴* will be tightened, so that the motion transmitted from the pulley *S'*, through the belt *S³*, to the small pulley *w* will also be transmitted through the belt *S⁴*, belt-wheel *W'*, shaft *S⁵*, pinion *S⁶*, gear-wheels *E''* and *E'*, to the screw-shaft *E* and the carriage, a slow traversing motion of the carriage being the result if the knife-edge *p* is at this time in engagement with the screw-shaft. When the outer end of the lever *N* is depressed, a pin, *n*, projecting therefrom, will be engaged by the lower catch, *n'*, of a spring latch-lever, *R*, which holds the lever *N* in this position. By throwing the latch-lever to the right, the catch *n'* will be disengaged from the pin and the lever *N* will rise, the pin *n* being caught by the upper catch, *n''*, and the pinion *S⁶* will be then out of engagement with the wheel *E''* and the belt *S⁴* relaxed.

In the machine invented by William A. Leggo, heretofore referred to, and upon which my present invention is an improvement, the slow motion is given by means of a belt passing from a small loose pulley on the shaft *S* to

a belt-wheel upon a counter-shaft, and another belt passing from a small pulley on said counter-shaft back to a loose belt-wheel, which is mounted on the main shaft, and is automatically clutched to said shaft when rotated in the proper direction. The driving-belt pulley is shifted in one direction to engage directly with the main shaft, and in the opposite direction to engage with the loose pulley, from which motion is transmitted by a belt to the counter-shaft. My improvement obviously gives a much simplified construction of the slow-motion-transmitting devices, and has the additional advantage that when the pinion *S⁶* is depressed out of engagement with the wheel *E''* the belt *S⁴* will also be relaxed, and the strain and wear upon the parts and bearings will be materially decreased when the slow-motion devices are not in use.

In the apparatus of Leggo an alcohol-lamp in practice is placed within the drum for drying the ink with which the message is placed upon the drum, and in trimming, filling, and replacing this lamp considerable time is sometimes lost before the transmission can be commenced. In order to dry the ink rapidly and save this loss of time, I have supported the shell of the drum by means of a single series of radial arms, *a*, projecting from a hub, *A'*, which is fixed to the shaft *S*, these arms *a* being arranged at about the middle of the length of the drum and leaving an unobstructed space on each side thereof within the drum. Into the space at one side of the arms *a*, I lead a gas-pipe, *Q*, provided with a burner, *q*, near the arms, said pipe connecting with a suitable pipe, *Q'*, outside the drum, and which may be supported by the framing, as indicated in Fig. 2, or in any other suitable manner. When the gas is ignited at the burner, a sufficient degree of heat will be communicated to the drum to cause the rapid drying of the ink thereon, so that immediately on completion of the preparation of the message the transmission of the same may be commenced, either by shifting the carriage back and bringing the contact-roller in contact with the drum at the commencement of the message, and connecting the drum and carriage for fast motion, or by using devices which will reverse the motion of the carriage, and transmitting the message backward.

Having thus described my invention, what I claim is—

1. The combination, with the drum, the sliding carriage and contact-roller carried thereby, and the screw-shaft, of mechanism for engaging the carriage with said screw-shaft and simultaneously bringing the contact-roller in contact with the drum, substantially as described.

2. The combination, with the drum, the carriage-support, the sliding carriage, and the screw-shaft, of the pivoted arm *D*, having the spring *k* secured thereto, and carrying the contact-roller, the knife-edge plate *F*, secured to said arm and extending downward through

the carriage, and the pivoted disk L, provided with a suitable handle, and having the eccentric pin l' extending loosely through said arm D, substantially as described.

5 3. In an automatic telegraph-transmitter, the combination, with a drum for the reception of a message in non-conducting spaces, and actuated at will by one of two sets of gearing, one of which is adapted to give the drum a 10 much greater rate of speed than the other, of the gear-wheel E², mounted upon the drum-shaft and intermediately connected with the screw-shaft, the short shaft S³, carried by the

lever N, the pinion S⁶, mounted on the short shaft and arranged to mesh with said gear-wheel, the belt-wheel W', also mounted on said short shaft, and means for transmitting motion to said belt-wheel, substantially as described.

In testimony whereof I have hereunto set my 20 hand in the presence of two subscribing witnesses.

RUFUS ANDERSON.
